Primary Examiner — Cynthia Ramirez*Assistant Examiner* — Laura H Yu(74) Attorney, Agent, or Firm — Belles Katz LLC(57) CLAIM

The ornamental design for a swimsuit, as shown and described.

DESCRIPTION

FIG. 1 is a front view of a swimsuit showing my new design. FIG. 2 is a rear view thereof.

FIG. 3 is a left-side view thereof; and, FIG. 4 is a right-side view thereof.

The broken lines formed by linear segments of equal length in the figures are provided for environment only and form no part of the claimed design.

1 Claim, 4 Drawing Sheets(56)
